UNITED STATES PATENT OFFICE

2,475,867

ELECTRICAL SIGNAL ASSEMBLY

Jack Williams, San Pedro, Calif.

Application June 20, 1947, Serial No. 755,842

2 Claims. (Cl. 177—329)

1

This invention relates to an electrical signal assembly particularly useful for mounting portions of a signal system for use in offices, hospitals and the like, and the prime object of my invention is to provide a novel electrical signal assembly which can be mounted in the usual electrical outlet box.

Another object of my invention is to provide a novel electrical signal assembly which is simple in construction, inexpensive to manufacture and effective to operate, and in which the main base or frame consists of a metal stamping.

A feature of my invention is to provide a novel electrical signal assembly in which a plurality of electrical units used in a signal system are mounted on a base or frame, and are so arranged and mounted that the entire assembly will fit in the usual electrical outlet box.

Another feature of my invention is to provide a novel electrical signal assembly which is compact and in which the various parts of the assembly can be easily reached for repair or replacement.

Other objects, advantages and features of invention may appear from the accompanying drawing, the subjoined detailed description and the appended claims.

In the drawing:

Figure 1 is a rear elevation of my electrical signal assembly.

Figure 2 is a sectional view taken on line 2—2 of Figure 1.

Figure 3 is a plan view of the frame after it has been completed as a stamping, but prior to bending the various parts.

Referring more particularly to the drawing, my electrical signal assembly is mounted on the back of the usual face plate 1, which covers the electrical outlet box, all of which is usual and well known in the industry. My signal assembly consists of a frame 2 which is formed from a suitable sheet metal and is stamped in the shape shown in Figure 3. The ears 3—4 are bent upwardly along the lines 5—6 respectively, and a screw 7 extends through the face plate 1, and through the ear 3 to mount the frame on the back of the face plate. A threaded sleeve 8 extends through the face plate and through the ear 4, thus mounting the lower end of the frame 2. With these two attachments, the frame is fixedly attached to the back of the face plate 1. An ear 9 is bent upwardly from the frame 2 along the line 10 and a coil 11 is mounted on this ear. This coil is part of the operating mechanism of the switch 12.

A light socket 13 is bent upwardly along the line

2

14 and a signal light 15 screws into this socket. The signal light 15 is positioned back of a lens 16 in the face plate 1. One contact of the light 15 engages a terminal 17 which extends through the hole 18 in the frame 2. All of the terminals subsequently described are of the same type, that is, they consist of a threaded shank and lug nuts threaded to the shank and bearing against each side of the frame plate 2, thus holding the terminal in position.

A switch terminal 19 is mounted in the hole 20 in the frame 2. A second switch terminal 21 is mounted in the hole 22 of the frame 2. A push button 23 extends through the sleeve 8, and the inner end of the switch button is bifurcated to fit over the pin 24, which is mounted in the hole 25 of the frame 2. In the structure previously described, the frame 2 extends substantially at right angles to the face plate 1, and the various parts of the electrical signal assembly are attached to this frame and consequently are mounted either parallel to the frame or at right angles to the frame. Therefore, the various units are completely assembled, and the entire arrangement can be mounted in the usual electrical switch box. Furthermore, by removing the face plate 1, the entire assembly is removed and all of the parts thereof can be viewed and can be replaced, or repaired, as necessary.

30 Having described my invention, I claim:

1. An electrical signal assembly comprising a frame formed of sheet metal, an electrical face plate, a pair of mounting ears bent from said frame, a mounting screw extending through one 35 of said ears, and a push button assembly extending through the other of said ears, said mounting screw and push button assembly extending through the electrical face plate, whereby the frame is mounted to the electrical face plate, a light socket bent from the frame and adapted to receive an electrical lamp, said face plate having a hole therein aligned with the electrical lamp and a lens mounted in said hole, a coil bracket bent from the frame, a plurality of electrical terminals mounted on the frame, said frame having holes therein, each of said holes receiving a terminal, and a pin and terminal mounted in said frame, and engaged by the push button, said frame having a hole therein to receive said pin.

50 2. An electrical signal assembly comprising a frame formed of sheet metal, an electrical face plate, a pair of mounting ears, integrally formed with and bent from said frame, a mounting screw extending through one of said ears, and a push button assembly extending through the other of

said ears, said mounting screw and push button assembly extending through the electrical face plate, whereby the face plate is attached to said frame, a light socket integrally formed with and bent from the frame, said socket receiving an electrical lamp, said face plate having a hole therein aligned with the electrical lamp and a lens mounted in said hole, said frame having a hole punched therein, adjacent the socket, a terminal fixedly mounted in the hole, said terminal being engaged by one terminal of the electrical lamp, a plurality of additional holes in said frame, a terminal fixedly mounted in each of the last named holes, said last named terminals consisting of a switch operable by said push button as-

10

15

sembly, and a coil bracket integrally formed with and bent from said frame, and adapted to mount a coil.

JACK WILLIAMS.
